SYNCHRONISM INDICATING MEANS

Filed July 22, 1927

Inventor:
Emmett F. Carter,
by *Emmett F. Carter*
His Attorney.

UNITED STATES PATENT OFFICE

EMMETT F. CARTER, OF SCHENECTADY, NEW YORK, ASSIGNOR TO GENERAL ELECTRIC COMPANY, A CORPORATION OF NEW YORK

SYNCHRONISM INDICATING MEANS

Application filed July 22, 1927. Serial No. 207,785.

My invention relates to synchronism indicating means and more particularly to means for indicating a condition of synchronism between a plurality of sources of voltage at a remote point by means of high frequency currents transmitted through space, or over wire line conductors such as those of the usual power distribution system.

It is often necessary in connection with the operation of the usual power distribution systems, that a generator located in a substation be started and connected to the system, by an operator at a remote point, such as at the power dispatcher's station. By means of remote control equipment now well-known in the art this may be conveniently effected provided the operator at the dispatcher's station be furnished with reliable indications as to the relative condition of the voltage of the generator with respect to that of the system. It is necessary to the synchronizing operation that the operator should be reliably informed as to the relative magnitude of the voltage of the generator with respect to that of the system, as to whether the frequency of the generator being synchronized is greater or less than that of the system, as to the relative direction of phase rotation of the voltage of the generator and that of the system and finally as to when the condition of synchronism has been attained.

One of the purposes of my present invention is to provide means whereby the above indications may be had at the operator's station in an economical, reliable and satisfactory manner. Another purpose of my invention is to provide means whereby the above indications may be had by means of high frequency currents transmitted either through space, as by radio, or over wire line conductors such as those of the distribution system involved. A further purpose of my invention is to provide means whereby the above indications may be had by means of a single high frequency channel thereby permitting other available channels on the distribution conductors, or in space, as the case may be, to be used for signaling, control, or other purposes, as desired.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing, in which the single figure illustrates one embodiment of my invention.

Referring to the drawing, 1 indicates an electrical circuit which is shown as of the polyphase type and which may comprise that of a single generator or that of the usual more complicated distribution system. 2 represents a generator which may be located at a substation on the distribution system and which is adapted to be synchronized with and connected to the circuit 1 by means of a switch 3. The equipment illustrated at A comprises that which is located at the substation, or in the neighborhood of the generator 2, and that which is illustrated at B comprises the equipment located at the operator's or power dispatcher's station. For the purpose of controlling the generator 2 and the switch 3 by the operator at the station B any suitable type of remote control equipment, not shown, may be employed. Since my invention relates only to means for furnishing the required indications at the station B the necessary control equipment will not be here set forth.

At the station A is located an oscillation generator 4 which is adapted through the coupling condenser 5 to supply high frequency alternating currents to the grid circuit of an amplifier 6, the output circuit of which is connected through a transformer 7 and conductors 8 to the circuit 1. The oscillation generator 4 and the amplifier 6 may be of any suitable construction but in the case shown they are of the three element electron discharge type, the cathode circuits of which are energized through a circuit 9, transformer 10 and conductors 11, the latter of which are connected to one phase of the circuit of the generator 2.

12, 13, 14 represent transformers corresponding in number to the number of phases

of the generator 2 and circuit 1. The primary winding of each of these transformers is connected through conductors 15, 16, 17 respectively to corresponding phases of the generator 2 and circuit 1 and across each phase of the connecting device 3. Associated with the secondary circuit of each of these transformers is a rectifying device 18, 19, 20 respectively, each of which may be of the usual two element electron discharge type and which are connected in a manner to supply rectified potential from the transformers 12, 13, 14 to the anode circuit of the oscillation generator 4 and the amplifier 6. The circuit of these devices includes the spaces between the cathodes and anodes of these devices, secondary windings of the transformers 12, 13, 14, conductor 21, conductor 22, conductor 23, cathode circuit 9 of the oscillation generator 4 and amplifier 6, spaces between the cathodes and anodes of the generator 4 and amplifier 6, anode reactors 24 and 25, and the cathode circuit of the devices 18, 19, 20. This latter cathode circuit is likewise energized through the transformer 27 from the conductors 11. It will thus be seen that at any instant when an alternating current potential appears across any pair of contacts of the polyphase switch 3 direct current potential will be supplied from the devices 18, 19, 20 through the circuit previously traced to the anodes of the oscillation generator 4 and the amplifier 6, thereby rendering these devices operative to supply high frequency currents of proportionate magnitude through the transformer 7 and circuit 8 to the distribution system 1.

At the remote point, or dispatcher's station B, is provided a detector, or rectifying device 28, which may also be of the three element discharge type and which is connected through a circuit 29, transformer 30 and circuit 31 to the distribution circuit 1. The circuit 29 includes suitable inductance 32 and condenser 33 by means of which it may be tuned to the frequency of the carrier currents transmitted by the generator 4 and amplifier 6. In the anode circuit of the device 28 is connected a direct current indicating means 34, primary winding of the transformer 35 and the usual source of anode potential 36.

With the equipment as thus far described, if it be assumed that the generator 2 is running with the proper phase rotation with respect to that of the voltage of circuit 1, but the condition of synchronism has not as yet been attained an alternating current potential will appear simultaneously across primary windings 12, 13, and 14, this potential being rectified and supplied to the anode circuit of the devices 4 and 6, rendering them operative to supply pulsations of high frequency current to the circuit 1 and hence to the rectifying device 28, thereby producing a response upon the indicating device 34. The frequency of the pulsations will be equal to

the beat frequency between the voltages of the sources 1 and 2, with the result that as synchronism is gradually approached the needle of the ammeter 34 will be seen to vibrate back and forth over its scale between limits determined by the maximum and minimum magnitudes of the received carrier and with a frequency which is directly indicative of the difference between the frequencies of the two sources. By this means the operator is informed as to the proper time to close the switch 3; namely, when the vibrations of the needle are sufficiently infrequent to indicate that synchronism has been practically attained and when the needle registers a minimum of received carrier.

If the phase rotation of the source 2 happens to be reversed from that of the voltage on the circuit 1 then plate voltage will be continuously applied to the anode circuit of the devices 4 and 6, there being small periodic pulsations therein which are of high frequency and small magnitude as compared with the pulsations which occur when the directions of phase rotation are alike. Thus the meter 34, when the phase rotations are in opposite directions, will register a plate current which has a magnitude intermediate the maximum and minimum which occurs when the direction of phase rotation are alike and also having a considerably smaller average value. This current will also have smaller pulsations therein than is the case when these phase rotations are alike, these characteristics indicating to the operator that the phase rotation of the machine 2 is incorrect.

It will thus be seen that with the arrangement as thus far described, the operator is furnished with an indication as to the proper direction of phase rotation of the voltage of the source 2 and also with an indication as to when the two voltages are in synchronism and of proper relative magnitude if the directions of phase rotations are alike. It is also desirable that the operator be furnished with information as to whether the machine 2 is running too fast or too slow so that he may be informed as to what adjustments are necessary in order to bring the machine 2 into synchronism. To this end a device 37 is provided which may, if desired, comprise a synchronoscope of well known construction, such as that disclosed in Patent No. 685,155 P. M. Lincoln or any other suitable means operable responsively to the relative frequencies of the sources 1 and 2. A stationary coil 38 which is wound upon a U-shaped magnetic core 39 is energized from one phase 65 of the generator 2. Two rotatable coils 40 and 41 which are disposed at right angles to each other are located in inductive relation to the coil 38 and the magnetic core 39, the former of these coils being connected across a phase of the circuit 1 corresponding to phase 65 of the source 2.

through an inductance 42 and the latter being connected to the same phase through a resistance 43. Since this arrangement is now well-known in the art a further description thereof will not be given. Mounted upon the 5 axis of the rotatable coils 40 and 41 and adapted to rotate therewith is a disc 44. 45 represents an arm which is pivoted at its mid-point about a point near the circumference of the disc 44 one end of which frictionally engages the disc 44 and the other end of which is free. On opposite sides of the free end of the arm 45 are two pairs of contacts 47 and 48, the arrangement being such that if the coils 40 and 41, and therefore 10 the disc 44, rotate in a clockwise direction, as would be caused if the frequency of the source 2 were greater than that of the circuit 1, then the contacts 47 will be pressed into engagement by means of the arm 45, whereas if the rotation of the coils 40 and 41, and therefore 15 the disc 44, be in a counterclockwise direction as would be the case if the frequency of the source 2 were less than that of the circuit 1, then the contacts 48 will be pressed into engagement. The purpose of this will presently be set forth. 49 represents a constant speed motor on the shaft of which is mounted 20 a slip ring 50 and a pair of commutators 51 and 52. Each of these commutators comprises a plurality of conducting segments which are separated from each other about the circumference of the commutator by suitable 25 insulation, and each of which are electrical- 30 ly connected to the slip ring 50. The commutator 51 is connected in a circuit leading from slip ring 50 through the primary winding of the modulation transformer 53, source of potential 54, conductor 55, contacts of the 35 relay 56, conductor 57 and brush 66 which engages the commutator 51. The commutator 52 is connected in a circuit leading from the collector ring 50 through the primary winding of the modulation transformer 53, 40 source of potential 54, conductor 55, contacts of the relay 58, conductor 59 and brush 67 which engages the commutator 52. The secondary winding of the modulation transformer 53 is connected between the cathode 45 and the grid of the amplifier 6. The actuating coils of the relays 56 and 58 are adapted to be energized through circuits including the contacts 47 and 48 respectively, conductor 60, source of potential 54 and conductor 55. The contacts of these relays are preferably slightly slow in opening, this feature rendering the relays less sensitive to chattering of the contacts 47 and 48. The operation 50 of this portion of my device is as follows. If it be assumed that the frequency of the source of potential 2 is greater than that of the voltage on the circuit 1, then the disc 44 will rotate in a clockwise direction, thereby 55 through the arm 45 causing the contacts 47 to be closed and energizing the relay 56. This relay then closes its contacts, thereby 60 energizing the circuit of the primary winding of modulation transformer 53 through the collector ring 50 and commutator 51, and causing the output current transmitted from the amplifier 6 to be modulated by currents 65 determined in character by the spacing of the segments of the commutator 51. Likewise if the frequency of the source 2 be less than that of the voltage of the circuit 1, then the disc 44 will rotate in a counterclockwise direction and the arm 45 will be actuated to 70 close the contacts 48, and thereby energize the relay 58. The relay 58 then closes its contacts to energize the circuit of the primary 75 winding of the modulation transformer 53 through the collector ring 50 and the commutator 52, thereby causing the output current from the amplifier 6 to be modulated by currents determined in character by the 80 spacing of the segments of the commutator 52. Thus, for example, if it be supposed that the segments of the commutators 51 and 52 are equally spaced about the circumference 85 but that the segments of the commutator 51 are greater in number than those of the commutator 52 the two commutators being of equal diameter, it will be seen that when the frequency of the generator 2 is greater than 90 that of the circuit 1, the output currents from the amplifier 6 will be modulated by alter- 95 nating currents of a certain frequency, whereas if the frequency of the source 2 be less than that of the circuit 1 then the output current from the amplifier 6 will be modulated by alternating currents of a certain lesser frequency. Associated with the secondary winding of the transformer 53 in the output circuit of the rectifier 28 at the receiver are any suitable means 61 and 62 for 100 indicating to the operator the character of the modulating currents. This may constitute an audible device such as a pair of head phones, or, for example, in the case supposed above, where the modulating currents are 105 distinguished in character by the frequency the device 61 may comprise a tuned relay operable responsively to the modulating frequency when the generator 2 is running too fast and the device 62 may comprise a tuned 110 relay operable responsively to the modulating frequency when the generator 2 is running too slow. If desired the device 61 may be caused to energize a visible indicating device 63 and the device 62 may be caused to 115 energize a visible indicating device 64, the former being effected through conductor 68, source of potential 69 and conductor 70; and the latter being effected through conductor 68, source of potential 69 and conductor 71. 120 It will thus be seen that the operator at the station B by observing the magnitude of the received carrier and that of the pulsations therein as indicated by the indicating 125 130

device 34 may determine the direction of phase rotation of the machine 2, and if this direction be correct he may determine when the condition of synchronism has been attained. 5 Likewise by means of devices 61 and 62, or if desired, by devices 63 and 64, he may determine respectively whether the generator 2 be running too fast or too slow. Consequently, it will be noted that with my device as shown and described, the operator at a remote station B is furnished with all of the indications necessary to the synchronizing operation and that he is thereby enabled by means of his remote control equipment to control the generator 2 and the switch 3 in a manner such that the generator 2 may be safely connected to the circuit 1.

While I have shown a particular means for modulating the carrier it will, of course, be understood that any suitable means may be employed. Likewise while I have shown a particular device 37 for operating the contacts 47 and 48 it will, of course, be understood that any means which is operable responsive to the relative frequency of the source 2 and the circuit 1 may be used. In a similar manner I have shown means for varying the intensity of the carrier in accordance with the voltage across the connecting means 30 3. It will, of course, be understood that any means for varying the carrier in a known relation to the voltage across this connecting means may be employed.

While I have shown and described a particular embodiment of my invention, it will, of course, be understood that I do not wish to be limited thereto since many modifications both in the circuit arrangement and in the instrumentalities employed may be made without departing from the spirit and scope of my invention as set forth in the appended claims.

What I claim as new and desire to secure by Letters Patent of the United States is:

1. In combination, an alternating current circuit, an alternating current generator adapted to be connected thereto, connecting means therefor, a transmitter connected to transmit high frequency currents varying in intensity responsive to the voltage across said connecting means and means responsive to said high frequency currents.

2. In combination, an alternating current circuit, an alternating current generator adapted to be connected thereto, connecting means therefor, a transmitter, means for continuously varying the intensity of the output from said transmitter responsive to the voltage across said connecting means, and means at a remote point adapted to be supplied with currents from said transmitter.

3. In combination, an alternating current circuit, an alternating current generator adapted to be connected thereto, connecting means therefor, a transmitter of alternating

currents adapted to be energized responsive to the voltage across said connecting means, thereby to transmit alternating currents varying in intensity in accordance with the voltage across said connecting means, rectifying means for said alternating currents and indicating means responsive to the rectified current to indicate the condition of voltage across said connecting means. 70

4. In combination, an alternating current circuit, an alternating current generator adapted to be connected thereto, connecting means therefor, a transmitter, means for varying the output currents from said transmitter in a known relation to the voltage across said connecting means, additional means for modulating the output currents from said transmitter in accordance with the relative frequency of the voltages appearing on opposite sides of said connecting means and means at a remote point responsive to said modulated output currents. 80

5. The combination, with a plurality of alternating current sources adapted to be synchronized with each other, of means for interconnecting said sources, a vacuum tube transmitter, means for energizing the anode circuit of said transmitter in response to the voltage across said interconnecting means, and means responsive to the output currents 90 from said transmitter. 95

6. The combination, with a plurality of alternating current sources adapted to be synchronized with each other, of means for interconnecting said sources, a vacuum tube transmitter of high frequency currents, means for energizing the anode circuit of said transmitter in accordance with the voltage across said interconnecting means, means for producing variations in said high frequency currents determined in character by the relative frequency of voltages on opposite sides of said interconnecting means and means at a remote point responsive to the intensity of said high frequency currents and to said variations. 100 105

7. The combination, with a plurality of alternating current sources adapted to be synchronized with each other, of means for interconnecting said sources, a high frequency transmitter of the electron discharge type, rectifying means adapted to be energized in accordance with the voltage appearing across said interconnecting means for supplying anode potential dependent thereon to said transmitter and means at a remote point responsive to the intensity of the high frequency currents transmitted by said transmitter. 110 115

8. In combination, a circuit having alternating current potential impressed thereon, an alternating current generator, means for connecting said generator to said circuit, a carrier current transmitter, means for varying the output from said transmitter in ac- 120 125 130

- cordance with the voltage across said connecting means, means for modulating said carrier currents with currents having either of two characters dependent upon whether the frequency of said generator be greater or less than that of said circuit and means at a remote point responsive to the intensity of said carrier and the character of said modulating currents.
10. In combination, a circuit having alternating current voltage impressed thereon, an alternating current generator, means for connecting said generator to said circuit, a carrier current transmitter, means for varying the output from said transmitter in accordance with the voltage across said connecting means, means for modulating said transmitter operable when the frequency of said generator is greater than that of said circuit, 70 means for modulating said transmitter operable when the frequency of said generator is less than that of said circuit, each of said modulating means being adapted to produce variations in said carrier of a different character and means at a remote point responsive to the intensity of said carrier and the character of said variations. 80
10. In combination, a circuit having alternating current voltage impressed thereon, an alternating current generator, means for connecting said generator to said circuit, a carrier current transmitter, means for varying the output from said transmitter in accordance with the voltage across said connecting means, a plurality of means for producing variations in said carrier of different characters, means responsive to frequencies of said generator greater than that of said circuit for establishing an operative circuit for one of said last mentioned means, and to frequencies of said generator less than that of said circuit for establishing an operative circuit to another of said last mentioned means and means at a remote point responsive to the intensity of said carrier and the character of said variations. 90
11. In combination, a circuit having alternating current voltage impressed thereon, an alternating current generator, means for connecting said generator to said circuit, a carrier current transmitter, means for varying the output from said transmitter in accordance with the voltage across said connecting means, means for modulating said carrier currents with currents having either of two frequencies dependent upon whether the frequency of said generator be greater or less than that of said circuit, and indicating means at a remote point responsive to the intensity of said carrier and to the frequency of said modulating currents. 100
12. The combination, with a plurality of polyphase alternating current sources adapted to be synchronized with each other, of means for interconnecting said sources, a carrier transmitter, a plurality of transformers, the primary winding of each of said transformers being connected between corresponding phases of said sources across said interconnecting means, rectifying means associated with the secondaries of each of said transformers and adapted to energize said transmitter in accordance with the voltage across said interconnecting means, means for producing variations in said carrier currents 75 determined in character by the relative frequency of the voltages of said sources and indicating means responsive to the intensity of said carrier and to the character of said variations. 85
13. In combination, a plurality of polyphase alternating current sources, a carrier current transmitter and means for energizing said transmitter in a manner determined by the relative direction of phase rotation of said sources. 95
14. In combination, a plurality of polyphase alternating current sources, a carrier current transmitter and means for varying the output from said transmitter in accordance with the relative frequency and direction of phase rotation of said sources. 100
15. In combination, a circuit having alternating current impressed thereon, an alternating current source adapted to be connected thereto, a transmitter, means for varying the output currents from said transmitter in accordance with the relative frequency of the voltages of said source and said circuit, and means for additionally varying said output currents in either of two manners dependent upon whether the frequency of said source be greater or less than that of said circuit. 105
16. In combination, a plurality of polyphase alternating current sources, a transmitter, means for varying the output currents from said transmitter in accordance with the relative directions of phase rotation of said sources, and means for modulating said output currents in accordance with the relative frequency of said sources. 110
17. In combination, a line having alternating electromotive force impressed thereon, an alternating current source to be synchronized with said line, an electron discharge device having an output circuit, means for energizing said discharge device in response to a resultant of electromotive forces of said source and line, a device, and means for controlling said device in response to current in said output circuit. 115
18. In combination, a source of alternating electromotive force, a second source of alternating electromotive force, switching means for connecting said sources together, a transformer having a primary winding and a secondary winding, one side of said primary winding being connected across said switching means, means for rectifying the voltage across the secondary of said trans- 120
- 125
- 130

former, a second transformer energized with alternating currents, and means for controlling the output current from said second transformer in response to said rectified current.

5 19. In combination, a source of alternating electromotive force, a second source of alternating electromotive force, switching means for connecting said sources together, means

10 for rectifying the potential existing between said sources, a thermionic discharge device having an output circuit, and means for controlling the current in said output circuit in response to rectified current produced by said

15 rectifying means.

20 20. In combination, a plurality of alternating current sources, a high frequency transmitter arranged to transmit a carrier wave having a constant frequency, and means for modulating said carrier wave in a manner determined by the relative frequency of said sources.

25 21. In combination, a plurality of poly-phase alternating current sources, a high frequency transmitter, and means for controlling the output current from said transmitter in response to the relative direction of phase rotation of said sources.

30 22. In combination, a pair of sources of alternating current, a carrier wave transmitter, and means for modulating the carrier wave transmitted by said transmitter in either of two different manners dependent upon the relative frequency of said

35 sources, said carrier wave being modulated in one of said manners when the frequency of one of said sources is higher than that of the other and in a different manner when the frequency of said one source is lower than that

40 of the other.

In witness whereof, I have hereunto set my hand this 21st day of July, 1927.
